COMBINATION TRUNK AND COT

Kendel J. Terrell, St. Louis, Mo.

Application July 5, 1943, Serial No. 493,515

1 Claim. (Cl. 190—2)

This invention relates to trunk and cot combinations, wherein a foldable cot, especially constructed for the purpose, is mounted at the top of a conventional trunk, and arranged in such manner that the cot may be opened out for use as desired, or may be folded up within the top of the trunk and the trunk lid closed down thereover, as in moving from place to place.

The prime object of the invention is to provide, in combination, a conventional form of trunk having a hinged lid, a foldable cot frame especially constructed for the purpose and mounted at the top of the trunk, the same being formed of a plurality of open loops pivotally connected together in such manner that the outer or end loops may be folded over inwardly upon and into the main or central loop which is anchored at the top of the trunk body, for permitting the trunk lid to be closed thereover, or so that the said loops may be opened out in the form of a complete cot, and a foldable covering supported upon the cot frame.

Another object of the invention is to provide, in combination with a conventional trunk having a deep lid hinged to the rear upper margin of the trunk body, a foldable cot frame supporting a foldable covering, and mounted at the upper side of the trunk, the said cot frame including open, rectangular loops hingedly connected, with the central or body loop supported at the top of the trunk body with the end bars of this loop raised somewhat above the upper margin of the trunk and set inwardly therefrom for permitting the trunk lid to be closed thereover, and the opposite side bars of this loop lowered to substantially the level of the said upper margin of the trunk for allowing the necessary sag room of the cot covering, with the head or pillow loop hingedly or pivotally connected with the rear bar of the body loop for folding inwardly into the body loop, with the thigh loop similarly connected with the frontal bar of the body loop and the frontal bar thereof similarly lowered to provide sag room for the cot covering, this said loop being also foldable rearwardly into the body loop, and a foot loop similarly connected with the thigh loop at the outer cross bar thereof and also foldable inwardly and rearwardly into the thigh loop, and with the latter into the main or body loop as mounted at the top of the trunk, and supporting legs hingedly or pivotally connected with the thigh loop and with the foot loop for folding up into those loops, for enabling the entire assembly to be folded up into the top of the trunk as desired, or to be opened out and extended for use as a cot.

With the foregoing objects in view, together with such other objects and advantages as may

appear from the following specification, attention is directed to the accompanying drawings as embodying certain preferred structures of the invention, and wherein:

5 Figure 1 is a perspective view of the foldable cot frame as mounted at the top of a conventional trunk, the assembly being constructed in accordance with this invention, the lid of the trunk being shown opened and the cot frame being unfolded from the trunk and extended as for use, fragments of the cot covering being also shown as marginally secured to the adjacent bars of the frame.

10 Figure 2 is a fragmental detail on an enlarged scale, for illustrating the method of securing the cot covering to the frame, and forming the margins of the covering at the junctures of the loops.

Figure 3 is a top plan view on the scale of Figure 1, showing the cot frame as folded together 15 within the upper and open side of the trunk, preparatory to closing the trunk lid thereover, a fragment of the said lid being shown as in its open position.

Figure 4 is a transverse section on the line 20 25 4—4 of Figure 3.

Figure 5 is a detail view in perspective, of a modified structure for removably supporting the main or body loop of the cot frame within the trunk body, so that the cot may be entirely removed from the trunk for independent use, when desired.

This invention is designed for mounting upon any conventional form of trunk, as represented generally at 5, and including the bottom 5a, sides 35 5b, ends 5c, and the deep lid 5d, hinged marginally by means of hinges 6 to the rear upper margin of the trunk.

The invention comprises a number of rectangular loops pivotally connected, and adapted to 40 fold together into the top of the trunk, or to unfold therefrom and open out to form an elongated cot frame for supporting a canvas or other flexible covering. The rectangular loops forming the cot frame are preferably made of metal tubing for the sake of lightness and strength. These loops include a main, rectangular body loop referred to generally at 7 and made up of pairs of spaced side bars 7a and spaced end bars 7b, joined together at their ends to complete the loop 7, 45 which is dimensioned to conform with the area of the trunk opening, but slightly less in length and width, so that the trunk lid 5d may be closed down thereover. The end bars 7b of the loop 7 are anchored to the ends of the trunk 5c in a raised relation to the upper margins of the trunk ends, as shown in Figure 1, by means of metal straps 8, which are riveted at their ends to the

bars and to the upper margins of the trunk ends respectively, as shown at 9. The frontal and rear side bars 7a of this loop, however, are dropped or down-set medially, substantially to the level of the upper margins of the trunk sides 5b, as clearly shown in Figure 1, for the purpose of allowing sag room for the flexible cot covering, and as will later be more fully explained. However the ends of the side bars 7a are not thus dropped or down-set, but remain at the level of the end bars 7b, for the purpose of providing pivot bearings as indicated at 7c. The elevation of the end bars 7b above the upper margins of the trunk ends corresponds substantially with the depth of the trunk lid 5d, and so that the latter may close down thereover.

A rectangularly U-shaped head loop shown generally at 10, and having its ends turned aside in parallel planes, is pivoted at these turned ends to the pivot bearings 7c of the rear bar of the body loop 7, this pivotal connection being effected by flattening these turned extremities of the arms and bending them nicely and freely around the bearings 7c, as indicated at 10b. The down-turned or offset end portions of the arms or ends of the loop 10 are indicated at 10a. The dimensioning of the loop 10 is such that it may be folded forwardly down into the top of the trunk 5 and within the loop 7, the offset ends 10a serving in this folded position to lower the loop 10 to the level of the upper margins of the trunk. Thus this head loop 10 may be unfolded rearwardly into the open trunk lid 5d, when the cot as such is in use, or as stated may be folded down into the top of the trunk when not in use.

A similar U-shaped thigh loop 11 is similarly pivotally connected at the free ends of its arms to the raised bearings 7c of the frontal side bar of the main or body loop 7, and the outer or forward cross arm or bar thereof is similarly off-set, or in its opened position is down-set medially, as indicated at 11a, to correspond with the off-setting of the frontal bar 7a of the loop 7, thus similarly providing the lateral raised bearings 11b at either end of this frontal bar. A pair of supporting legs 12, cross braced by the straps 13, is similarly pivoted as at 12a to the off-set medial portion of the forward bar 11a, these legs being of such length as to fold upwardly into the loop 11, or to open downwardly for supporting the loop 11 in its open position. Similarly a U-shaped foot loop 14 is pivoted at its flattened ends, as indicated at 14a, to the raised bearings 11b of the loop 11, and a pair of legs 15, cross braced by the straps 16, is pivoted at their flattened inner ends to the cross bar of this foot loop, as indicated at 15a, and these legs are thus adapted to fold up within the loop 14.

A suitable canvas or other form of flexible covering 17 is provided and is stretched over the expanded cot frame as thus formed, this covering being secured at its margins at sides and ends to the aligned side and end bars of the loops of the frame, in any conventional manner, as by forming a heavy marginal seam 18 around the covering, the latter being cut away as indicated at 19, at the several joints of the loops of the cot frame, so as to permit the ready folding of the covering along with the folding of the loops, when the assembly is folded up into the trunk. Grommets 25 are then seated in regularly spaced relation along and through this seam 18, and a heavy cord 24 is passed through these grommets and spirally around the adjacent bars of the cot frame. The ends of the cord 24 are brought to-

gether at one end of the frame and tied with a bow-knot 26. Thus the covering may be drawn taut as desired, or may be loosened for facilitating the folding of the loops and covering into the trunk as desired.

In Figure 5 is shown a modified method of removably supporting the cot frame within the trunk, so that the cot may be removed for independent use if desired, or so that the trunk may be used independently.

In this modification the body loop of the cot frame, in lieu of being anchored to the upper margins of the trunk ends, is anchored at its ends to the end boards 20 by the straps 8m and rivets 9m, the boards 20 being adapted to nicely slide within the ends of the trunk. Socket brackets 21 are anchored at 22 on the inner sides of these boards in vertically spaced relation, and cross-rods 23 with turned ends 23a are provided for bracing these end boards 20 in rigid upright position, by passing the ends 23a into the sockets 21 in crossed relation as shown. Thus the cot may be removed from the trunk and set up for independent use. Otherwise the rods 23 and boards 20 may be stored within the trunk with the boards 20 at the trunk ends, where they will stand upright.

If the trunk is wide enough the foot loop might be eliminated, since the other loops might then suffice for forming the cot frame, or the loops might be mounted lengthwise at the top of the trunk, thus providing longer though somewhat narrower loops for the cot frame.

While I have here shown and described certain embodiments of the invention, and preferred structural features thereof, it is understood that the structural features and arrangements as here shown may be modified or altered as desired, within the scope however of the claim.

I claim:

In a device of the kind described for mounting horizontally at the top of a conventional trunk having a deep lid hinged to the rear side top margin thereof, comprising a foldable cot frame for supporting a foldable covering and dimensioned as folded to fit within the top of the trunk with the lid closable thereover, the said frame including a closed rectangular body loop for positioning horizontally at the top of the trunk body, means for supporting said loop in raised position relatively to the upper margin of the trunk body a U-shaped head loop pivotally connected at the free ends of its end bars with the rear cross bar of the body loop, the width of the said U-shaped head loop substantially corresponding to the width of the lid and therefore adapted to rest for support when opened out, upon the outer margin of the opened lid, a U-shaped thigh loop pivotally connected at the free ends of its end bars with the frontal cross bar of the body loop, a U-shaped foot loop pivotally connected at the free ends of its end bars with the cross bar of the thigh loop, the cross bars of the body loop and of the thigh loop being down-set medially when in their extended position for allowing sag room for the cot covering, and legs pivotally connected at their inner ends to the cross bars of the thigh loop and of the foot loop and arranged to fold up thereinto, whereby the entire assembly may be folded up together and within the top of the trunk, with the trunk lid closable thereover, or may be extended out longitudinally for use as a cot.
